Primary Examiner — Paula Allen Greene*(74) Attorney, Agent, or Firm* — Tim Tingkang Xia, Esq.; Locke Lord LLP(57) **CLAIM**

The ornamental design for a wireless headset, as shown and described.

DESCRIPTION

FIG. 1 is a front perspective view of a wireless headset according to our new design;

FIG. 2 is a front perspective view thereof from another angle;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plain view thereof;

FIG. 8 is a bottom plain view thereof; and,

FIG. 9 is a perspective operational view thereof.

The broken lines illustrating portions of the wireless headset and/or environmental structures of the wireless headset form no part of the claimed design.

1 Claim, 9 Drawing Sheets(56)
